UNITED STATES PATENT OFFICE.

LOUIS F. HAGEMANN, OF NIAGARA FALLS, NEW YORK, ASSIGNOR TO AMERICAN SALES BOOK COMPANY, LIMITED, OF TORONTO, ONTARIO, CANADA, A CORPORATION OF ONTARIO, CANADA.

AUTOGRAPHIC REGISTER.

Application filed December 8, 1920. Serial No. 429,069.

This invention relates to apparatus for intermittently feeding and aligning strips, or webs of paper, and with respect to its more specific features, to the feeding, and aligning 5 of superposed paper webs associated in a manifolding autographic register, together with the efficient storing of one or more of the webs in the register.

One of the objects of the invention is the 10 provision of a simple and practical apparatus of the character referred to for gathering the unsevered webs, or one of them, into a compact bundle, or roll, and accurately aligning 15 or registering the printed forms, or other indicia, on succeeding portions of the web or the webs.

Another object of the invention is the provision of an efficient and practical device for taking up the webs, or one of them, which 20 nevertheless permits the web attached thereto to accurately align or register relative to the machine, or relative to other webs in superposed relation to the web to be taken up.

Another object of the invention is the provision of construction of simple and practical character for the purposes referred to, which 25 may be readily taken apart or assembled for threading, mounting, cleaning, repairing, 30 etc.

The invention accordingly consists in the features of construction, combinations of elements and arrangement of parts which 35 will be exemplified in the construction hereinafter set forth, and the scope of the application of which will be indicated in the following claims.

In the accompanying drawings forming 40 part of this specification, wherein similar reference characters refer to similar parts throughout the several views,—

Figure 1 is a side elevation of an autographic register embodying the invention herein referred to;

Fig. 2 represents a longitudinal vertical section of Fig. 1;

Fig. 3 is a view of the feed end of the register with the door thrown down, the take-up roller and certain adjuncts being shown in 50 vertical section;

Fig. 4 is a longitudinal vertical section of the feed end of the register, showing the feed

and take-up enlarged over Fig. 2 for a clearer disclosure, and

Fig. 5 is a plan view of the register, the 55 handle being in section.

Figs. 6, 7 and 8 represent details of the register.

Referring now more specifically to the drawings, the register embodies a light metallic frame providing end walls 1 and 2 and two side walls 3 forming a chamber for the reception of the webs or rolls of record strip, three of which rolls are illustrated at 4, 5, and 6. In the present embodiment each roll 60 65 may rest upon bottom flanges 7 fastened to the sides 3 and also upon inclined ways, or plates 8, supported by the side plates 3. From each of the rolls 4, 5 and 6, the several webs are passed around guide rollers 9, 10 and 11, 70 respectively, over a platen 13' and thence between the feed rolls of the machine, all as illustrated in Fig. 2. From this construction it will be perceived that when the webs are pulled or fed to the right in Fig. 2, the 75 rolls 4, 5 and 6 tend to be drawn up the inclines 8 and thereby exert a certain tension upon the respective webs tending to retract the webs. It is to be understood, however, that any other practical form of web tensioning means is within the purview of this invention or the natural tension of the web may suffice in some instances.

The feeding of the webs is effected by a feed roller and cooperative member adapted 85 to grip the webs. As illustrated, the cooperative member is also a roller. The numeral 12 indicates a shaft, journaled in the side walls of the frame, provided with a handle 13 for rotating the same and having a pair of feed discs, or feed rolls or rollers, 14 which operate in conjunction with the cooperative member, or roller, 15 to grip and feed the webs lying therebetween. Each web has a series of similar forms printed thereon as indicated, for instance, by the lines 16, and between the successive forms each web has one or more aligning apertures, in the present instance, two apertures 17, of which one appears in Fig. 3, transversely in alignment with each other, the successive apertures being longitudinally in alignment with the discs 14. Certain portions of the gripping surfaces of the discs 14 are of a narrow width

to enter the apertures 17 when the latter come between these discs and the roller 15 so that at that time the particular web is relieved from the grip of the feed rolls, and 5 in consequence the feed of the web ceases notwithstanding rotation of the discs 14.

In the present embodiment the machine has a top, or cover 18, hinged to the sides 3 at 19, at the feed end of the frame, so that the cover 10 may be turned on its hinge so as to permit access to the chamber and interior parts. The upper feed roller 15 has bearings or journals, 20 at each end which lie in slots 21 in the end walls 22 of a housing 23 at the front 15 end of the cover, said housing being an arched chamber integral with the cover 18. The bottom walls of the slots 21 are formed by removable plates 24 held in place by screws. The journals 20 bear, at times, on the plates 20 24 and are spring-pressed downwardly by springs 25 pressing against the followers 26. The proportion of parts is such that when the cover 18 is in the closed position, as illustrated in Fig. 2, for instance, the upper roller 25 15 is spring pressed towards the discs 14, the journals 20 being lifted somewhat off the bearing plates 24. Thus there is a resilient gripping effect by the feed rolls on the webs.

In the present embodiment the peripheral 30 dimension of the disc 14 is slightly greater than the distance between successive sets of apertures 17 so that one rotation of these discs feeds the webs an amount approximately equal to the distance between the successive sets of 35 apertures whereupon the advance of the webs by the web feed device ceases and the rotation of the disks 14 is arrested. The numeral 27 indicates a stationary stop on the side of the frame of the machine, being a pin bolted in 40 position. The handle 13 is slideable on a sleeve 28 projecting from the crank arm 29 and has a pin 30 slideable therewith into and out of a path intersecting the stop 27. A spring 31 is employed to press the pin 30 into 45 a path intersecting the stop 27.

The feed device is provided with means to start the feed of the paper webs after their advance has been arrested by the apertures coming between the feed rolls, which means 50 also cooperates to hold the webs in their relative aligned position attained. In the present embodiment the starting and holding means is provided by widening the discs 14 for a short portion of the periphery thereof. 55 As illustrated each disc is in effect widened, by being provided with the laterally disposed curved plates 40 which may be cast integrally therewith or bolted thereto and are flush with the edges of the discs. These plates, or web holding and starting devices, are disposed to grip the webs at the sides of the apertures 17 at intervals.

One end of the roller 15 is provided with gear teeth 41 which mesh with teeth of a gear 60 42 rotating with the shaft 12 so that rotation

of the two feed rollers is positively effected, one in conjunction with the other.

The numerals 43 indicate pins which are separate from the feed mechanism and are adapted to register the two upper webs relative to each other and to the machine when applying the webs to the machines. These pins are stationary when the machine is operated, and are mounted upon the front end of the machine in advance of the line of grip 75 between the feed rolls so as to permit the webs to readily move thereover and to be disengaged therefrom upon an advance movement of the webs. The pins 43 are transversely in alignment with each other and longitudinally in alignment with the apertures 17. They are placed at a readily accessible portion of the machine in front of the feed mechanism and in this embodiment are on the door which forms the front wall. 85

The numeral 44 indicates the tearing bar which, in the present embodiment, is formed by the lower front edge of the housing 23. It will be observed that the tearing bar 44 moves with the cover 18 on the hinge or pivot 19, said cover being pivoted at the points 19 through the instrumentality of the arms 45 extending from each side of the front end of the cover. When the cover is lowered to the position illustrated in Fig. 2 it may be locked 95 down by any suitable means.

The numeral 50 indicates a receptacle for carbon paper sheets which are intended to extend laterally between the webs and the free ends of the carbon paper sheets may be held 100 at the other side of the machine by some appropriate device.

The numeral 55 indicates a pawl pivoted on the inner face of one of the plates 3 and adapted to engage a tooth 56 on a collar on the 105 shaft 12 just before or at the instant the pin 30 engages the stop 27. The pawl 55 cooperates with the pin 27 to resist the accidental operation of the feed rolls in either direction when the webs are held by the plates 40. 110

It will be understood that should the distance between the successive sets of apertures 17, be greater than the peripheral length of the feed disks, as, for instance, twice as great, the feed disks may be turned twice to bring 115 up the next set of apertures to position between the feed rolls.

A web take-up device is provided and is located within the chamber of the machine so that the webs, or web, gathered thereupon 120 may be concealed and unauthorized access thereto prevented. This take-up device in the present embodiment includes a take-up spool or roller 57, connected for operation to the web feed means and, in the present instance, operating to take up the lowermost web, indicated at 58, the two other webs 59 and 60 passing out of the register beneath the tearing bar 44 and over the inwardly extending end of the front wall 1, which wall may 130

be hinged at its bottom at 61 thereby providing a door which may be thrown open to permit access to the take-up device and may be closed and locked to prevent access thereto.

5 Supported by, and having one end journaled in a side frame of the machine is a rotatable shaft 62 which extends through the spool 57 in axial alignment with said spool. On one end of this shaft is fixed a gear 63 which lies in a recess in a side frame 3 and meshes with an intermediate pinion 64, which latter in turn meshes with the gear 42, so that upon rotation of the gear 42 by operating the handle 13, rotation of the shaft 62 is effected.

10 On one end of the shaft 62 at the side of the pinion 63 is rotatably mounted a bearing piece 65 having a flange 66 adapted to bear against the outside of the frame wall 3, the piece 65 being kept on the shaft by a suitable washer 67. The piece 65 is as large or larger in diameter than the shaft 62 and the gear 63 and lies removably in an opening, or seat 68, in the side wall 3, when the shaft 62 is in operative position, being kept in said 15 opening by a keeper 69 pivoted to the side frame 3 at 70 which keeper may be moved out of contact with the piece 65 and permit the latter and the parts attached thereto to be withdrawn from the machine through the 20 opening 68. The shaft 62 may rotate relative to the take-up spool 57. Concentrically mounted on this shaft is a sleeve 71 rotatable relative to the shaft 62 and to the take-up spool or roller 57, and around the sleeve 71 is coiled a spring 72 positively attached at one 25 point or end 72' to the spool and at a different point or end 73' to the sleeve 71, so that rotation of the sleeve 71 in a direction to take up the web tends to move the ends of the spring 30 72 relative to each other and so increase the tension of the spring when the rotation of the take-up roller is arrested.

In the embodiment illustrated the take-up spool 57 may be actuated from the web feeding means through the train of connections including gears 42, 64 and 63, the shaft 62, the sleeve 71 and spring 72. The shaft 62 cooperates with the sleeve 71 to form a friction clutch, or connection, adapted to yield 45 and permit operation of the feed means while the take-up spool 57 is held from rotation. As illustrated, the shaft 62 is composed of a rod having an intermediate portion slotted and expanded to have sufficient frictional contact against the inner face of the sleeve 71 to cause said sleeve to rotate with the shaft 62 unless effectively restrained.

The numeral 73 indicates a web attaching bar which rotates with the take-up roller and 50 to which the end of the web to be taken up may be attached. This bar is movable transversely of the axis of the take-up roller and has arms 74 passing through the ends of the roller and adapted to contact the surface of the shaft 62 when the latter is in operative 55

position in the sleeve 71. In this wise the bar 73 is held in an outer position permitting the web to be readily wrapped therearound for attachment. Upon the withdrawal of the bar 73 from the take-up spool, or roller, 70 the bar 73 may be moved into contact with the surface of such spool so as to permit the spool to be more readily withdrawn from the accumulation of web coiled therearound. The expansion of the intermediate portion 75 of the shaft 62 results in the smaller ends thereof which may contact with the arms 74, as stated.

At times in the operation of the register it is desirable to arrest the operation of the take-up roller and also to arrest rotative displacement of that end of the spring 72 which is operatively connected to the take-up roller. To this end one end of the take-up roller 57 has fixed thereto a ratchet-wheel 75, and a pawl 76 pivoted to a side frame of the machine at 77 may be actuated from the web feeding means so as to permit it to be urged into engagement with the ratchet wheel to arrest rotation of the latter or to be withdrawn from the ratchet wheel to permit rotation of the latter and take-up spool connected thereto. In the present embodiment the pawl 76 has an arm 78 to which is connected a spring 79, which spring tends to move the pawl into engagement with the teeth of the ratchet wheel. The upper end 80 of the arm of the pawl, when the latter is in engagement with the ratchet wheel, lies in the path of one or more rotatively translatable lugs or pins 81 adapted to successively actuate the pawl and free the same from engagement with the ratchet wheel at predetermined times. The lugs 81 are carried on the face of the gear wheel 42 and move the 85 pawl in opposition to the spring 79.

The machine may be threaded by first throwing up the cover 18 on its hinges 19 and opening the door which is hinged at 61. The web supply rolls 4, 5, and 6 may then be 90 placed in position upon the bottom flanges 7 and the webs drawn from these rolls and passed around the respective guide rollers 9, 10, and 11 and in superposed relation over the platen 13'; thence over the lower feed 95 rollers or disks 14. Suitable transfer, or carbon sheets, may be placed between the intermediate web and the ones above and below it above the platen 13', and these carbon sheets may be drawn from a roll or rolls lying 100 in the receptacle 50 at one side of the frame 105 of the machine. The opposite ends of the carbon sheets may be held in place by any suitable device at the other side of the machine. The front end of the bottom web is 110 then attached to the attaching bar 73 while the bar is held in its outer position by contact with the shaft 62. A turn or two of the handle 13 will roll up a portion of the web on the lower end of the take-up spool. The door 115

1 may then be closed, first lifting the advance ends of the two outer webs so as to permit the inner end of the door to enter between the lower web and the one above it. Preliminary alignment of the two outer webs may then be effected by pulling each until a set of aligning apertures engages the pins 43. Preferably, at this time, the aligning apertures in the lower web should be in front of the rollers 14 a distance equal to the distance of the pins 43 from the upper edge of the rollers 14. The cover may then be lowered so as to cause the upper feed roller 15 to cooperate with the rollers 14 to yieldingly grip the webs. By then turning the handle 13 the webs may be fed and the lower web taken up on the spool 57 until the next set of aligning apertures comes between the feed rolls, permitting the webs to align, and so that a slight further feed operation will cause the plates 40 to advance the webs slightly and hold them. The handle 13 will then be in contact with the stop 27 and retrograde rotation of the lower feed rolls prevented by the pawl 55. The webs will then be held in alignment ready for inscription and for the tearing off of the advance ends of the two upper webs on the tearing bar 44.

Before the grip on the webs is relieved by the aligning apertures coming between the feed rolls, rotation of the take-up spool 57 is arrested by the pawl 76, one of the pawl-actuating pins 81 releasing this pawl and permitting the spring 79 to urge the pawl into engagement with the teeth of the ratchet wheel 75. This stoppage continues until the webs are held by the plates 40. But as the feed operation continues the webs advance and slack is produced in the lower web 58 between the feed rollers and the take-up spool. Upon the relief of grip consequent upon the aligning apertures coming between the feed rollers, alignment of all the webs may take place under the influence of the tension, or tendency of the webs to retract, and it will be observed that the slack provided in the lowermost web at this time permits this web to retract rearwardly and align itself with the others, notwithstanding the fact that this web is attached to and will ultimately be rolled up on the take-up spool. After this aligning the plates 40 take hold as above stated.

After inscription, the feed operation causes the release of the pawl 76 from the ratchet 75 so that the spring 72 acts as a motor and expends a part of its energy in rotating the take-up spool to take up the slack in the lower web 58, this taking up of slack being effected preferably before the hold by the plates 40 is released, so as to avoid jerking the lower web out of alignment with the others. Thereafter the webs are simultaneously fed by the feed rollers for almost a complete revolution before the next set of aligning ap-

tures arrive in position to relieve the grip of the feed rollers on the webs. At one or more points during this revolution the pawl 76 may hold the take-up spool from rotation with the result that the connections between the web feeding devices and the sleeve 71 will rotate said sleeve and thereby potentialize or tension the spring 72, which latter, as has already appeared, is yieldingly coupled on one side for actuation through the connections leading to the feed means and on the other side is positively attached to the take-up device. Eventually the clutch connection between the shaft 62 and the sleeve 71 may yield and prevent over tensioning and possible fracture of this spring.

In order to remove the roll of web accumulated upon the take-up spool 57, the keeper 69 is thrown from in front of the bearing piece 65 to permit this piece together with the shaft 62 and the gear 63 to be withdrawn laterally through the opening 68 in the frame in which the bearing piece 65 is seated. The removal of the shaft 62 relieves the attaching bar 73 and permits it to collapse against the roller 57. Thereupon the take-up spool and the attaching bar carried thereby, together with the roll of web on the spool, may be drawn out of the chamber of the machine, and the take-up spool together with the attaching bar readily withdrawn from the center of the roll of web.

To reset the take-up spool in position for a new supply of web, the spool is first introduced into the chamber of the machine and then the shaft 62 introduced through opening 68 so as to extend through the take-up spool, the bearing piece 65 being eventually seated in the opening 68, whereupon the gear 63 will be in mesh with the gear 64 and the machine be ready to receive a new supply of web.

Thus, by the above described construction are accomplished, among others, the objects hereinbefore referred to.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent, is:—

1. An apparatus of the character described comprising, in combination, means for feed-

- ing a plurality of webs and for bringing the same into alignment, a web take-up device having resilient means for maintaining tension upon one of said webs during feeding action of said feeding means, and means for relieving said tension of said take-up at intervals during feeding action of said feeding means so as to permit free web aligning action of said feeding means.
- 10 2. A device of the character described comprising, in combination, means for feeding a plurality of webs, and for bringing the same into alignment, a web take-up device, means for driving the take-up device from the feed, including a spring adapted to exert resilient tension upon the web, and locking mechanism automatically operated for locking at intervals said take-up device against take-up action during feeding operation of said feeding means.
- 15 3. An apparatus of the character described, comprising in combination, means for feeding a web, a web take-up device, and means for operating said take-up device including a resilient member stressed by actuation of the feeding means so as to exert resilient tension upon the web during the feeding operation.
- 20 4. An apparatus of the character described, comprising in combination, means for feeding a web, a web take-up device, means for operating said take-up device adapted to exert resilient tension upon the web during the feeding operation, and means for locking said take-up device against the operation of said operating means at a given point in the feeding operation.
- 25 5. In an apparatus of the character described, in combination, web feed means, a web take-up device, a train of connections between said take-up device, and said feed means adapted to actuate said take-up device to effect web take-up during feeding actuation of the feed means, said train including a spring motor interposed in the connections, and a yielding coupling in said train connected to said spring motor on the side thereof leading to said feed means.
- 30 6. In an apparatus of the character described, in combination, a web feed means, a web take-up device, and a train of connections between said take-up device and said feed means adapted to actuate said take-up device from said feed means, including a spring interposed in the connection to permit arrest of said take-up device during operation of said feed means, said spring being yieldingly coupled in the train on the side leading to said feed means and positively attached, on the other side, to said take-up device.
- 35 7. In an apparatus of the character described, in combination, web feed means, a web take-up device, a train of connections between said take-up device and said feed means adapted to actuate said take-up device from said feed means, including a spring interposed in the connection to permit arrest of said take-up device during operation of said feed means, said spring being yieldingly coupled in the train on the side leading to said feed means and positively attached, on the other side, to said take-up device.
- 40 8. In an apparatus of the character described, in combination, web feed means, a web take-up spool, a train of connections between said spool and said feed means adapted to rotate said spool from said feed means including a spring positively attached at one point to said spool and frictionally coupled in the train at another point, a ratchet on said spool, a pawl to cooperate with said ratchet, and one or more pawl actuating pins to be actuated by said feed means.
- 45 9. In an apparatus of the character described, in combination, web feed means, a web take-up spool, a train of connections between said spool and said feed means adapted to rotate said spool from said feed means including a rotatable shaft in said spool, a sleeve on said shaft frictionally coupled thereto, a coil spring surrounding said sleeve and attached at different points to said sleeve and said spool, and means adapted to be actuated by said feed means for arresting rotation of said spool.
- 50 10. In an apparatus of the character described, in combination, web feed means, a web take-up spool, a train of connections between said spool and said feed means adapted to rotate said spool from said feed means including a rotatable shaft in said spool, a sleeve on said shaft frictionally coupled thereto, a coil spring surrounding said sleeve and attached at different points to said sleeve and said spool, and means adapted to be actuated by said feed means for arresting rotation of said spool, including a ratchet on said spool, a pawl to cooperate with said ratchet, and one or more pawl actuating pins to be actuated by said feed means.
- 55 11. In an apparatus of the character described, in combination, means to intermittently feed a web and to release the web during intermissions in the feed, a web take-up device, and means to provide slack between the web feed and the take-up device when the web is first released.
- 60 12. In an apparatus of the character described, in combination, means to intermittently feed a web and to release the web during intermissions in the feed, a web take-up device, means to provide slack between the web feed and the take-up device when the web is first released, including a spring motor potentialized by the web feed, and means to restrain the operation of the motor, released by the web feed.

13. In an apparatus of the character described, in combination, web feed means, a web take-up device, a spring-motor adapted to operate said take-up device, one end of the spring of said motor being operatively connected to said take-up device, means operatively connected to the other end of said spring adapted to move said last mentioned end relative to the other end by operation of said feed means, and means adapted to arrest movement of the first mentioned end of said spring.
14. In an apparatus of the character described, in combination, web feed means, a web take-up device, a spring-motor adapted to operate said take-up device, one end of the spring of said motor being operatively connected to said take-up device, means operatively connected to the other end of said spring adapted to move said last mentioned end relative to the other end by operation of said feed means, and means operable by said feed means adapted to arrest movement of the first mentioned end of said spring.
15. In an apparatus of the character described, in combination, web feed means, a web take-up device, a spring-motor adapted to operate said take-up device, the spring of said motor being operatively connected to transmit power from said feed means to said take-up device, and locking mechanism for locking said take-up device against take-up action by said spring.
16. In an apparatus of the character described, in combination, means adapted to feed a web, a take-up roller, a spring operatively connected for rotation with said take-up roller, means for rotating said take-up roller from said feed means through said spring, a take-up roller arresting device operable by said feed means, said take-up roller rotating means including a sleeve rotatable relative to said take-up roller and to which one end of said spring is connected, a removable rotatable shaft in said sleeve frictionally coupled to the latter, and a web attaching bar carried by said take-up roller, movable transversely thereof, and adapted to be held in its outer position by said shaft.
17. In an apparatus of the character described, in combination, web feed means including a feed disk adapted to grip the web and enter aligning apertures therein, a web take-up spool, means adapted to rotate said spool from said web feed means including a friction clutch adapted to permit operation of said web feed means without rotating said spool, and means, actuated automatically by feeding operation of said web feed means adapted to arrest rotation of said spool when said disk enters said aligning apertures.
18. In an apparatus of the character described, in combination, web feed means including a feed disk adapted to grip the web and enter aligning apertures therein, a web take-up spool, means adapted to rotate said spool from said web feed means including a shaft and a sleeve each rotatable relative to said spool, a coil spring connected at one point to said spool and at another point to said sleeve, and means, operable from said feed means, adapted to arrest rotation of said spool when said disk enters said aligning apertures.
19. In an apparatus of the character described, in combination, web feed means including a feed disk adapted to grip the web and enter aligning apertures therein, a web take-up spool, means adapted to rotate said spool from said web means including a shaft and a sleeve each rotatable relative to said spool and forming a friction clutch adapted to permit operation of said web feed means without rotating said spool, a coil spring connected at one point to said spool and at another point to said sleeve, and means, operable from said feed means, adapted to arrest rotation of said spool when said disk enters said aligning apertures.
20. In an apparatus of the character described, in combination, web feed means including a feed disk adapted to grip the web and enter aligning apertures therein, a web take-up spool, means adapted to rotate said spool from said web feed means including a shaft and a sleeve each rotatable relative to said spool and forming a friction clutch adapted to permit operation of said web feed means without rotating said spool, a coil spring connected at one point to said spool and at another point to said sleeve, means, operable from said feed means, adapted to arrest rotation of said spool when said disk enters said aligning apertures, a spool-arresting dog, a spring adapted to urge said dog into position to arrest rotation of said spool, and one or more rotatively translatable pins moved by said feed means to cause withdrawal of said dog from spool-arresting position.
21. In an apparatus of the character described, in combination, web feed means including a pair of feed disks adapted to grip the web and enter aligning apertures therein, a web take-up spool, a shaft in said spool, rotatable relative thereto and geared to said web feed means, a sleeve in said spool, frictionally engaging said shaft and rotatable relative to said spool and said shaft, a spring coiled around said sleeve and attached at one point to said spool and at another point to said sleeve, a ratchet wheel rotatable with said spool, a pawl for engaging said ratchet wheel, and one or more pins rotatively translatable by the feed means to free said pawl from said ratchet wheel at predetermined times.
22. In an apparatus of the character described, in combination, web feed means including a pair of feed disks adapted to grip the web and enter aligning apertures therein,

- a web take-up spool, a shaft in said spool, rotatable relative thereto and geared to said web feed means, a sleeve in said spool, frictionally engaging said shaft and rotatable relative to said spool and said shaft, a spring coiled around said sleeve and attached at one point to said spool and at another point to said sleeve, a ratchet wheel rotatable with said spool, a pawl for engaging said ratchet wheel, one or more pins rotatably translated by the feed means to free said pawl from said ratchet wheel at predetermined times, and web-holding devices rotatable with said disks, adapted, at intervals, to grip the web 15 to one side of the apertures.
23. In an apparatus of the character described, in combination, web feed means including a pair of feed disks adapted to grip the web and enter aligning apertures therein, a web take-up spool, a shaft in said spool, rotatable relative thereto and geared to said web feed means, a sleeve in said spool, frictionally engaging said shaft and rotatable relative to said spool and said shaft, a spring coiled around said sleeve and attached at one point to said spool and at another point to said sleeve, a ratchet wheel rotatable with said spool, a pawl for engaging said ratchet wheel, one or more pins rotatably translated by the feed means to free said pawl from said ratchet wheel at predetermined times, and a web attaching bar, rotatable with and transversely movable of said spool, having arms 25 adapted to contact said shaft.
24. In a device of the character described, in combination, means, adapted to feed a plurality of superposed webs having aligning apertures spaced apart longitudinally of the webs, including a feed roller and a cooperative member to grip said webs, a portion of the periphery of said roller being narrower than said apertures and adapted to enter said apertures to permit longitudinal adjustment of said webs, take-up means, for one of said webs, including a web take-up roller operatively connected for actuation from said feeding means, a spring-motor connected for actuating said take-up roller, spring-motor tensioning mechanism operatively connected for actuation from said feed means; the operative connections between said feed means, and said take-up roller and tensioning mechanism, including a clutch adapted to yield upon predetermined resistance to actuation of said take-up roller and upon predetermined tensioning of said spring-motor, and means, controlled by said feed means, adapted, at times, to arrest actuation of said take-up roller.
25. In an apparatus of the character described, in combination, means to feed superposed webs intermittently and to release the webs during the intermission, a web take-up device, and means adapted to provide slack in the web between the feed means and the take-up device during the release of the webs.
26. In an apparatus of the character described, in combination, means to feed superposed webs intermittently and to release the webs during the intermission, a web take-up device, means adapted to provide slack in the web between the feed means and the take-up device, and means adapted to operate said take-up device from said feed means including a connection adapted to yield and permit operation of the feed means without operation of the take-up device while the webs are released.
27. In an apparatus of the character described, in combination, means to feed superposed webs intermittently and to release the webs during the intermission, a web take-up device, means operable by the feed means adapted to arrest the operation of said take-up device while continuing the feed of the webs, and means adapted to operate said take-up device from said feed means including a connection adapted to yield and permit operation of the feed means without operation of the take-up device while the webs are released.
28. In an apparatus of the character described, in combination, means adapted to grip and feed superposed webs, a web take-up device for one of said webs, means adapted to provide slack in the latter web between the feed means and the take-up device, and means adapted to relieve the grip on said webs after the provision of said slack.
29. In an apparatus of the character described, in combination, means adapted to grip and feed superposed webs, a web take-up device for one of said webs, means adapted to provide slack in the latter web between the feed means and the take-up device, means adapted to relieve the grip on said webs after the provision of said slack, thereby permitting the webs to align relative to each other, and means adapted to cause operation of said take-up device while the webs are being fed.
30. In an apparatus of the character described, in combination, means adapted to grip and feed superposed webs, a web take-up device for one of said webs, means adapted to provide slack in the latter web between the feed means and the take-up device, means adapted to relieve the grip on said webs after the provision of said slack, thereby permitting the webs to align relative to each other, means adapted to hold the webs in their relative aligned position, a spring-motor adapted to cause operation of said take-up device while the webs are held, and means adapted to tension said spring-motor by operation of said feed means.
31. In an apparatus of the character described, in combination, means adapted to

grip and feed superposed webs, a web take-up device for one of said webs, means adapted to provide slack in the latter web between the feed means and the take-up device, means 5 adapted to relieve the grip on said webs after the provision of said slack, thereby permitting the webs to align relative to each other, means adapted to hold the webs in their relative aligned position, a spring-motor adapted 10 to cause operation of said take-up device while the webs are held, and means adapted to tension said spring-motor by operation of said feed means, including a connection adapted to yield and permit operation of the 15 feed means without further tensioning said spring-motor.

32. In an apparatus of the character described, in combination, means adapted to feed superposed apertured webs including a 20 feed roller adapted to grip the webs, a web take-up device, means adapted to provide slack in the web between the feed means and the take-up device, said feed roller having a portion adapted to enter the apertures to relieve the grip on the webs, and means adapted 25 to arrest the operation of said take-up device until after termination of said relief of grip while continuing the feed of the webs.

33. In an apparatus of the character described, in combination, means adapted to feed superposed apertured webs including a feed roller adapted to grip the webs, a web take-up device, means adapted to provide slack in the web between the feed means and 35 the take-up device, said feed roller having a portion adapted to enter the apertures to relieve the grip on the webs and permit them to align relative to each other and a portion adapted to grip the webs at the side of said 40 apertures and hold the webs in their relative aligned position, and means adapted to cause operation of said take-up device while said last mentioned portion of said feed roller is holding said webs.

34. In an apparatus of the character described, in combination, a frame, a shaft rotatable in said frame, a rotatable take-up spool through which said shaft extends, a rotatable sleeve on said shaft frictionally 50 clutched thereto, said sleeve and spool rotatable relative to each other, a coil spring, through which said shaft and sleeve extend, attached to said sleeve and spool at different points, web feed means, spool arresting devices actuated from said feed means, and means for rotating said shaft from said web feed means.

35. In an apparatus of the character described, in combination, a frame, a shaft rotatable in said frame, a rotatable takeup spool through which said shaft extends, a rotatable sleeve on said shaft frictionally clutched thereto, said sleeve and spool rotatable relative to each other, a coil spring, through which said shaft and sleeve extend,

attached to said sleeve and spool at different points, web feed means, spool arresting devices actuated from said feed means, means for rotating said shaft from said web feed means, including a gear on said shaft rotatable therewith, said frame having an opening larger in diameter than said gear, a bearing piece rotatively attached to said shaft removably seated in said opening, and a keeper for said bearing piece.

36. In an apparatus of the character described, in combination, means to feed superposed webs intermittently and to release the webs during the intermissions, a web take-up device, and means adapted to arrest the operation of said take-up device while the webs are released.

37. In an apparatus of the character described, in combination, means to feed superposed webs intermittently and to release the webs during the intermissions, a web take-up device, and means adapted to operate said take-up device from said feed means including a connection adapted to yield and permit operation of the feed means, while the webs are released, without take-up operation of the take-up device.

38. In an apparatus of the character described, in combination, means adapted to grip and feed superposed webs, a web take-up device for one of said webs, means adapted to provide slack in the latter web between the feed means and the take-up device, means adapted to relieve the grip on said webs after the provision of said slack, thereby permitting the webs to align relative to each other, and means adapted to hold the webs in their relative aligned position.

39. In an apparatus of the character described, in combination, means adapted to grip and feed superposed webs, a web take-up device for one of said webs, means adapted to provide slack in the latter web between the feed means and the take-up device, means adapted to relieve the grip on said webs after the provision of said slack, thereby permitting the webs to align relative to each other, and means adapted to cause operation of said take-up device while the webs are held in alignment.

40. In an apparatus of the character described, in combination, means for feeding superposed webs, a web take-up device, driving connections between said feeding means and said take-up device for actuating the latter for take-up action during feeding actuation of the feeding means, means for checking take-up actuation of said take-up device during continued feeding actuation of the feeding means and a motor for driving said take-up device to effect take-up actuation thereof during feed actuation of said feeding means.

41. In an apparatus of the character described, in combination, means adapted to

feed superposed apertured webs including a feed roller adapted to grip the webs, a web take-up device, means adapted to provide slack in the web between the feed means and the take-up device, said feed roller having a portion adapted to enter the apertures to relieve the grip on the webs and permit them to align relative to each other and a portion

adapted to grip the webs at the side of said apertures and hold the webs in their relative aligned position and a motor adapted to cause operation of said take-up device while said last mentioned portion of said feed roller is holding said webs.

In testimony whereof I affix my signature.
LOUIS F. HAGEMANN.
